DRIVING MECHANISM FOR TURRETS AND
LIKE APPARATUSGunnar Swahnberg, Keene, N. H., assignor to
Kingsbury Machine Tool Corporation, Keene,
N. H., a corporation of New Hampshire

Application June 7, 1934, Serial No. 729,507

3 Claims. (Cl. 29—50)

The present invention relates to improvements in driving mechanisms for turrets and like apparatus, in which a member is cyclically advanced through a predetermined distance and then held against further movement.

An arrangement of this nature is illustrated but not claimed in the copending application of Edward J. Kingsbury, Serial No. 683,541, filed August 3, 1933.

10 A feature of the present invention is the employment of devices on the structure which is to be rotated and held, and a stepwise rotatable member having means thereon for engagement successively with and cooperating with said devices for cyclically producing the succession of rotative and holding effects.

Another feature of the present invention is the provision of a plurality of driving and stop elements located on the structure which is to be intermittently advanced and held, and an intermittently advanced rotatable member having projecting elements thereon engaged successively with said elements.

25 With these and other features in view, an illustrative form of practicing the invention is shown on the accompanying drawings, in which:

Figure 1 is a plan view of a machine tool turret unit embodying the present invention.

Figure 2 is a side elevation of the same, with parts broken away to show the relationship of internal structures.

Figure 3 is a detail view on a larger scale, corresponding to a portion of Figure 1, and having parts broken away to indicate a section substantially on line 3—3 of Figure 4.

Figure 4 is an upright sectional view substantially on line 4—4 of Figure 3.

In these drawings, a driving motor M operates to move a rotatable shaft 17 and the flange or collar 23 fixed thereto intermittently, under the control of a latch member which is released by a link 63 when the latter is energized by the solenoid 65. As a result of this release, the shaft 17 is given a fractional revolution, illustratively through 180 degrees, upon each actuation of the solenoid 65. The gear train and like parts by which this movement is effected may be of any desired character and form no part of the present invention. A mechanism excellently adapted for the purpose is illustrated in the aforesaid Kingsbury application, to which reference is made for a driving train employable for the purpose.

It will be understood that at the start and end of each cycle, the parts are in a relative position such as illustrated in Figure 1.

The flange 23 is illustratively provided with lugs 24 which extend into peripheral notches 70 of a turning plate 71 which is secured to the flange 23 by screws 72. The plate 71 has a plurality of shafts 73 thereon, extending parallel to the axis of shaft 17 in the illustrated form, and each bearing a roller 74a, 74b.

The general housing H of the turret mechanism supports a top plate TP having a circular flange TF at the periphery, and a central column 10 75 which is received within a sleeve 16 carried by the turret table TT. This turret table supports a plurality of work holding devices such as F (Figure 2) by securing means which are passed into the holes 10 of the turret table TT 15 (Figure 1). In the illustrative form, six such devices may be provided at six stations which are spaced equally in a circumferential direction, i. e. at 60 degrees from one another.

It will be noted that this illustrated form of 20 the structure provides for the securing of the flange TF on the turret table TT and its guiding by a closely fitting and overlapping flange on the top plate TP. By this means, all of the 25 rotating and holding devices on the rotatable member and on the rotatable structure are concealed and protected and yet are available for easy assembly and disassembly by raising the turret table from position and replacing it therein.

Corresponding to the number of stations thus afforded, the bottom of the turret table TT is provided with six driven elements 11a, 11b . . . 11e which are engaged successively by the rollers 74a, 74b and moved by the latter to 35 accomplish the indexing movement of the turret table TT. The gaps between the substantially rectilinear surfaces 11x of adjacent elements 11a, 11b . . . approximate the external diameter of the rollers 74a, 74b and provide grooves into which 40 one of these rollers advances toward the axis of table TT at the beginning of an indexing movement of the table TT, and in which the roller then retraces its course at the end of the indexing period. The outer ends of the elements have 45 arcuate curved surfaces 11x which are concentric with the circular shape of the plate 71 when the corresponding element is located in its final position (Figure 1) above the plate 71. It will be noted that each of the elements is therefore 50 substantially symmetrical about a line extending radially from the axis of rotation of the turret table TT; and that a surface 11x is tangential to a corresponding surface 11y.

While the turret is at a standstill, the parts are, 55

for example, in the position of Figure 1, with the two rollers 74a, 74b illustratively engaging a single element 11a and thus holding the turret table against movement as a result of tangential stresses in either direction applied to the turret table TT. The rollers 74a, 74b engage the element 11a at the aforesaid arcuate portions 11y thereof.

When a new indexing is to be accomplished, the cycle is started by energizing solenoid 65 in the illustrative form so that the motor M causes the shaft 17 and therewith the plate 11 to turn through 180 degrees in a clockwise direction in Figures 1 and 3. The upper roller 74a is thus caused to advance relatively toward the axis of rotation of the turret table TT, engaging in the groove between the adjacent elements 11a, 11e until the axis of this inwardly moving roller is in the line joining the centers of the shaft 17 and the axis of rotation of the turret table TT (position of Figures 3 and 4). The initial engagement of this roller 74a has caused an accelerating movement of the element 11a whose surface 11x is being pushed, and therewith of the turret table TT, in a counterclockwise direction.

After leaving the position of the roller 74a in Figure 3, this roller causes a continued advancement of the element 11a but at a decreasing rate.

The other roller 74b has at first moved outward along the corresponding aforesaid arcuate surface 11y of the element 11, and clears the same so that the element 11a may move in a counterclockwise direction past the roller. As the roller 74a passes from the intermediate position of Figure 3 toward the end position of Figure 1, the roller 74b moves relatively inward and engages an arcuate surface 11y of the succeeding element 11e. At the moment that the inwardly moving roller 74b encounters this surface 11y (corresponding to position 74ba in Figure 1), the outwardly moving roller 74a is just passing from the aforesaid groove onto its corresponding arcuate surface 11y of the same element 11e (corresponding to position 74aa in Figure 1). Between the positions 74ba and 74aa, and the positions of rollers 74a, 74b in Figure 1, therefore, there is essentially no rotative movement of the turret table TT and any peripheral strains exerted upon the turret table are absorbed by the rollers, so that the turret table is held fixedly at station.

Each of the elements 11a, 11b, etc., is of similar shape, resembling the shoe of a sad iron, and is successively engaged and held by the driving rollers 74a and 74b, so that each movement of 180 degrees of the shaft 17 produces an advancement of the turret table TT by an equal angular increment and presents the table in position at a new station. Each of these elements has the arcuate surfaces thereof extending for substantially equal angles at either side of the line A—A of Figure 1, which passes through the axis of shaft 17 and the axis of the two rollers while the latter are in the holding position. Thus, the outwardly moving roller escapes from and clears the element which has just been held at substantially the same time that the other roller passes onto the substantially rectilinear surface thereof for accomplishing a further advancement of the turret table; and also the roller which has been free enters upon an arcuate surface at substantially the same time that the roller which has been driving passes from the groove onto the corresponding arcuate surface of the element to be held.

The illustrated mechanism therefore permits the utilization of a rotative movement of 180 degrees from standstill to standstill of shaft 17 for accomplishing a lesser angular movement of the turret table, along with a locating and blocking of the turret table at the desired station when the shaft 17 is at a standstill, without the employment of any moving latches or like auxiliary parts.

Obviously, the invention may be employed in many other ways within the scope of the appended claims.

Having thus described the invention, what I claim as new and desire to secure by Letters Patent, is:

1. In a driving mechanism for turrets and like apparatus, a member intermittently rotated through 180 degrees, a turret structure to be advanced intermittently by equal angular increments of less than 180 degrees, two driving devices mounted eccentrically at diametrically opposite points on said member, and a plurality of driven elements on said structure equal in number to the number of said angular increments necessary to move the structure through a single revolution, each said element being constructed and arranged on said structure for driving by one said device while the other device is presented by said member out of position for engagement by said element, each said element including surfaces for engagement by both said devices simultaneously for holding the structure against movement while the member is at a standstill, said surfaces being presented to the devices substantially at a right angle to a line passing through the axis of said member and the points of contact of the devices with the said surfaces of the momentarily engaged element, so that relative stresses upon said structure do not produce rotative movement of said member whereby the turret structure is held immovable independent of any latching device.

2. In a driving mechanism for turrets and like apparatus, a member rotated intermittently through an angle of 180 degrees, a turret structure to be advanced intermittently by angular increments about an axis offset from the axis of said member, a plurality of circumferentially spaced elements fixed on said structure, each element being substantially symmetrical about a radial line from the axis of said structure and having at one end arcuate surfaces and also having substantially rectilinear surfaces tangential to said arcuate surfaces, the rectilinear surfaces of adjacent elements providing grooves which extend in substantially radial directions with respect to the axis of said structure, and eccentrically mounted rollers pivotally mounted on said member diametrically opposite one another and engageable in said grooves and with said surfaces, said member operating to present one said roller in a groove to drive said structure while holding another said roller clear of the elements, the two arcuate surfaces of one element being engaged simultaneously by said two rollers when the member is at a standstill of its intermittent movement whereby to hold the structure against movement by tangential stresses in either direction thereon, said arcuate surfaces of the element so engaged being presented during such standstill in concentric position with respect to the axis of said member so that the accuracy of positioning and maintaining of the turret structure is not affected by minor inaccuracies of positioning of the said rollers.

3. In a driving mechanism for turrets and like apparatus including a rotatable turret structure for intermittent advancement, a source of power, a member rotated cyclically by said source through a predetermined angle and thereafter detained against movement until the beginning of the next cycle, the combination therewith of a plurality of elements attached to said structure and spaced apart circumferentially, each 10 element having two arcuate surfaces and substantially rectilinear surfaces tangential thereto, said rectilinear surfaces of adjacent elements providing a plurality of grooves extending substantially radially with respect to the axis of said structure, and a pair of engaging devices located

on the member diametrically opposite to one another and eccentrically to the axis of rotation thereof and successively engageable against said arcuate surfaces and in said grooves during the rotation of said element, said engaging devices being located and positioned at the standstill of said element upon the said two arcuate surfaces of one said element with the axes of the rollers and of the member located in a line tangential to the turret structure and thereby operating to resist tangential stresses upon said structure and held the same immovable independently of any latching device. 5 10

GUNNAR SWAHNBERG.
